UNITED STATES PATENT OFFICE.

JAMES O. BEWAN, OF ONLEY, VIRGINIA.

PULL-ROD ATTACHMENT.

1,287,843.

Specification of Letters Patent. Patented Dec. 17, 1918.

Application filed January 22, 1918. Serial No. 213,147.

To all whom it may concern:

Be it known that I, JAMES O. BEWAN, a citizen of the United States, residing at Onley, in the county of Accomac and State of Virginia, have invented certain new and useful improvements in Pull-Rod Attachments, of which the following is a specification.

This invention relates to a pull rod attachment for pull rods or chains for igniting gas or other lights, as for example pull chains connected with electric switches. But I have designed it especially for use in connection with a friction ignition device for acetylene gas lights, which device forms the subject matter of a separate application filed Mar. 13, 1918, Serial No. 222,218.

This invention comprises as an attachment for the pull rod or chain, a luminous handle formed of two sections of glass secured together and having exterior facets with a luminous compound carried between the glass sections, the light from which is radiated in all directions from the facets, thereby making the entire attachment luminous in the dark.

The invention consists in the following described construction, definitely pointed out in the claims, and shown in the accompanying drawings in which:—

30 Figure 1 is a transverse section through my attachment, and

Fig. 2 is an inner face view of one of the sections of glass shown in Fig. 1. The term "glass" is used broadly to cover any transparent material, and the term "luminous paint" applies to any of the well known

light radiating compounds either in paste or semi-liquid form.

In constructing the attachment as shown I employ two sections of glass, 7 and 8 40 which are cemented together. An endless groove 9 is formed in the inner face of one of the sections, with a communicating groove 9^a leading to the outer edge or face of the section. A centrally arranged recess 10 is 45 also provided in one of the sections and this is coated as at 10^a with the luminous paint. In the drawing I have shown both the grooves and the recess as being formed in section 8. A wire 11 is inserted in the 50 grooves and projects from the outer end of the groove 9^a and terminates in an eye 12 to which a rod or chain may be connected.

The sections are preferably formed with facets and the light rays radiating from 55 the luminous compound are diffused through and magnified by said facets, so that it will be visible from any direction, and will appear to cover a greater surface than actually coated.

60 What I claim is—

A device of the kind described comprising two transparent sections, means for securing them together, a recess formed in the inner face of one section, a groove formed in the 65 face of one section and extending to the outer edge thereof, a luminous material arranged in the recess, and a pull rod attaching device inserted in said groove.

66 In testimony whereof I affix my signature. 70

JAMES O. BEWAN.
